200 YEAR CALENDAR

From Year 1800 to 2000

18 DIRECTIONS FOR OPERATING THIS 200 YEAR CALENDAR:
TURN DIAL TO YEAR WANTED. THEN REFER TO THE CALENDAR INDICATED BY THE NUMBER WHICH APPEARS
IN THE SQUARE BESIDE THE YEAR. FOR EXAMPLE: WHAT CALENDAR FOR THE YEAR OF 1868? TURN THE
DIAL UNTIL 1868 APPEARS TO THE LEFT ON THE CALENDAR. IN THE SQUARE FOR THE CALENDAR NUMBER
WE FIND NUMBER 11--THE CALENDAR NUMBER 11 IS THE CORRECT CALENDAR FOR THAT YEAR.

PERPETUAL CALENDAR

Emil E. Hansen, New York, N. Y.

Application November 10, 1932
Serial No. 641,965

5 Claims. (Cl. 40—107)

This invention relates to improvements in perpetual calendars.

An object of the invention resides in providing a perpetual calendar comprising a movable member, and a master calendar comprising a plurality of calendars arranged in sequence, said member having a plurality of rows of indicia arranged on the member, each row representing the last two numerals of a year date and the sequential order of a calendar of said master calendar corresponding to said year dates.

A further object of this invention is to provide a calendar in which a dial is rotatable between two elements, one of the elements exposing to view various numerals on the dial indicating years and calendar numbers, the dial being operated in conjunction with a series of numbered calendars attached to the device.

A further object of the invention is to provide a calendar giving the dates, days of the week and days of the year from the year 1800 up to and including the year 1999.

A further object of the invention is to afford advertising facilities, which advertising is done on the outside element of the calendar.

These and other objects of the invention and the means for their attainment will be more apparent from the following detailed description, taken in connection with the accompanying drawings, illustrating one embodiment by which the invention may be realized, and in which:

Fig. 1 is a front view of a calendar embodying and employing the invention.

Fig. 2 is a view showing a calendar embodying and employing the invention, with the front element removed to show the rotating disk and the plurality of master calendars.

The drawings show the invention in one of its forms. The numeral 1 indicates the outside element or cover which is provided with two pairs of windows 2 and 2' through which may be seen the selected number of the year 3 and the corresponding number of master calendar 4. The numerals 3, 4 and 3', 4' appear on dial 5 which is rotatably mounted to inside element or back 6 at 7. As illustrated in this instance, windows number 3 and 4 are used for the years 1800 to 1899 and 3' and 4' for the years from 1900 to 1999. The edge of dial 5 slightly protrudes as shown in Figure 1 at 8 to facilitate rotation of the disk or dial 5. Dial 5 is provided with four circular and spaced columns 9, 10, 11 and 12. Columns 11 and 9 represent respectively, the year and corresponding numerals for master calendar 13 for the years from 1900 to 1999. The first two

figures of the centuries are indicated at A. On account of numerals being read on both sides of disk, it is essential to print all numerals in columns 10 and 12 in a direction opposite to those in columns 9 and 11. The arrangement of 60 the numerals contained on the dial or disk 5 can be changed without changing the main purpose of the calendar.

Although the drawings show windows provided to expose the last two numbers of the 65 years, it is understood that the windows may be made larger to expose the whole year.

It is further understood that the edge of dial 5 may be serrated to facilitate manipulation.

The numeral 13 represents a series of master 75 calendars. As it happens, the possibilities for changing of week-days in respect to the days of the month are sevenfold for common years and sevenfold for leap-years, therefore, with the present system of time recording, fourteen master 80 calendars are sufficient to cover any past date back to the time when the present calendar system was adopted and up until such time when changes may be made in the present calendar system. It is understood that this invention 85 with necessarily slight changes may be adapted for use with any other yearly timing system.

The numeral 13 represents a series of fourteen yearly calendars, each numbered and each of which begins on the successive following day, as 85 for example, January 1st will appear on master calendar No. 1 on Sunday, on master calendar No. 2 on Monday, and on master calendar No. 3 on Tuesday, and so on until Saturday and repeating the same again for seven additional master calendars covering leap-years.

The master calendars 13 are suitably fastened to back element 6 as shown, for example by staples 14, but it is understood that any other fastening means may be employed. The numeral 95 15 indicates the master calendar number corresponding to numbers shown in columns 9 and 11 of the rotatable dial or disk 5. On the outside element 1 ample space is provided for advertising purposes and for a picture or illustration 100 16 if so desired. Suitable perforation 17 for hanging the device is provided.

Instructions or directions 18 are provided upon the outside element, preferably on its lower portion.

The disk 5 may be rotatably mounted directly to the back of outside element 1.

The arrangement of the numerals contained on the dial or disk 5 can be changed without altering the main purpose of the invention, also 110

any convenient symbols other than numerals may be employed to distinguish the master calendar.

In the accompanying drawings I have illustrated the invention embodied in one of its practical commercial forms but as this illustration is primarily for purposes of disclosure it will be understood that the invention is not limited to this particular form of structure and that it may be modified in many respects without departure from the true spirit and scope of the invention as herein defined and claimed. I wish it further understood that the terms which I have employed herein are used in a descriptive rather than in a limiting sense, except however for such limitations that may be imposed by the state of the prior art.

Having thus described my invention, what I claim as new and desire to secure by Letters Patent, is:

1. A device of the character described comprising a movable member and a master calendar comprising a plurality of yearly calendars arranged in sequence, said member having a plurality of rows of indicia arranged on the member, each row representing the last two numerals of a year date, the last two numerals of another year date reading in a direction opposite to those in the first row, and the sequential order of a calendar of said master calendar corresponding to each of said year dates.

2. A device of the character described comprising a rotatable disk and a master calendar comprising a plurality of yearly calendars arranged in sequence, said member having a plurality of rows of indicia arranged on the disk, each row representing the last two numerals of a year date, the last two numerals of another year date reading in a direction opposite to those in the first row, and the sequential order of a calendar of said master calendar corresponding to each of said year dates, and an element over said disk and provided with indicia representing the first two numerals of said year dates and cooperating with the last two numerals of said year dates to present full year dates.

3. A perpetual calendar comprising a series of fourteen yearly calendars arranged in a predetermined order, a rotatable member being provided with a group of the last figures of the year dates of a century circularly arranged in numerical sequential order, a second group of the last figures of the year dates of another century similarly arranged but reading in an opposite direction, a third group comprising indicia representing the numerical order of said yearly calendars and arranged for cooperation with year figures shown on said member, and reading in the same direction as one of the first two groups, a fourth group comprising indicia representing the

numerical order of said yearly calendars arranged for cooperation with year figures shown on said member and reading in the same direction as the other of the first two groups, the indicia of the third and fourth groups being arranged circularly and at the outer and inner extremities of said four groups, the first and second groups being arranged adjacent to each other and between the third and fourth groups so that the said groups appear in four columns with each indicium of the fourth group in alinement with the figures of the second group, and each indicium of the third group in alinement with the figures of the first group, and an element arranged over said member and provided with openings to respectively expose the figures and its corresponding indicium contained in the said four groups when the said member is rotated.

4. A perpetual calendar comprising a series of yearly calendars arranged in a predetermined order, a rotatable member being provided with a group of the last figures of a plurality of year dates circularly arranged in a predetermined order, a second group of the last figures of another plurality of year dates similarly arranged, but reading in an opposite direction, a third group comprising indicia representing the numerical order of said yearly calendars arranged for cooperation with year figures shown on said member and reading in the same direction as one of the first two groups, a fourth group comprising indicia representing the numerical order of said yearly calendars arranged for cooperation with year figures shown on said member and reading in the same direction as the other of the first two groups, the indicia of the third and fourth groups being arranged circularly, each indicium of the fourth group in alinement with the figures of the second group, and each indicium of the third group in alinement with the figures of the first group, and an element arranged over said member and provided with openings to respectively expose the figures and corresponding indicium contained in the said four groups when the said member is rotated.

5. A perpetual calendar comprising a series of yearly calendars arranged in a predetermined order, a rotatable member provided with a group of the last figures of a plurality of year dates circularly arranged in a predetermined order, another group comprising indicia representing the numerical order of said yearly calendar arranged for cooperation with the year figures on said member, the said groups being arranged so that each indicium is in alinement with each of the said figures, and an element arranged over said member and provided with openings to respectively expose the figures and its corresponding indicium when the said member is rotated.
